UNITED STATES PATENT OFFICE

RALPH C. STROUT, OF WOLLASTON, MASSACHUSETTS, ASSIGNOR TO THE WHITE TAR COMPANY OF NEW JERSEY, A CORPORATION OF NEW JERSEY

GARMENT BAG

Application filed March 7, 1930. Serial No. 433,917.

My invention relates to garment bags and particularly to bags of the moth-proof type that are usually constructed of paper or other suitable fibrous material.

5 An object of my invention is to provide a garment bag of simple construction and of sufficient strength at its corners and edges to prevent its being damaged under ordinary circumstances.

10 A further object of my invention is to provide a simple and convenient method of constructing garment bags whereby the edges and corners of the latter may be reinforced by the employment of material integral with 15 the bag.

In accordance with the present invention, I provide a novel method of folding the material for constructing a garment bag whereby when the bag is completed, the side, end and 20 corner portions are reinforced by additional thicknesses of material. The corners of the bag are reinforced by a relatively large number of thicknesses whereby the corners are usually rigid and resistant to wear or damage.

25 The details of my invention will be described in connection with the accompanying drawings in which:

Figure 1 is a side view in elevation of a bag constructed in accordance with my invention;

30 Fig. 2 is a reduced perspective view of the blank from which the bag is constructed;

Figs. 3, 4, 5 and 6 are views similar to Fig. 2 showing successive stages of construction of a portion of the blank of Fig. 2 to form a 35 corner of the bag; and

Fig. 7 illustrates a completed corner portion of the bag.

Referring to Fig. 1, a garment bag 1 constructed in accordance with my invention 40 comprises two sections of material 2 and 3. The section 2 is a relatively narrow strip extending longitudinally of the bag for half of its width, as shown. The section 3 constitutes the remainder of the side of the bag that is 45 illustrated, which may be considered the front of the bag, and also, all of the side of the bag which may be termed the back, and which does not appear in the drawings. The sections 2 and 3 are secured together by a seam 50 4 extending approximately through the cen-

ter of the front of the bag. The seam is formed by overlapping portions fastened by any suitable adhesive such as glue.

The ends of the bag are closed by a top fold or flap 5 and a bottom fold or flap 6. The left side of the bag, which is adapted to be opened, is normally closed by a series of successive folds, the outer one 7 of which appears in Fig. 1. These folds are retained in closed position by pivoted metal clips 8 that are suitably secured to the side of the bag.

The bag is adapted to be supported by a metal hook 9 that is pivotally secured to a metal plate 10, the latter being suitably riveted to the front of the bag through the top fold 5. The hook 9 is adapted to be suspended upon any suitable means, such for example as a rod 11.

In constructing the bag, the sections 2 and 3 are connected to form a suitable blank 13 shown in Fig. 2.

The description of the formation of the bag 1 from the blank 13 will be better understood by reference, also, to Figs. 3 to 7 which illustrate the several stages of construction with particular regard to a portion of the bag. These views illustrate a corner portion of the bag, for example, the lower right-hand corner of the bag of Fig. 1 and they include approximately the material of Fig. 2 that is 80 enclosed by dot-and-dash lines therein.

It will be noted that one portion of the blank 13 is wider than the remaining portion and the resulting side walls of the bag are of unequal length whereby their folded end edge 85 portions will be of unequal width as will be more clearly described.

The first step in the construction of the bag is the folding of the blank 13 along the lines 14, 15 and 16 to produce the fold 17, a 90 portion of which appears in Fig. 3.

The fold 17 is next folded against the wide portion of the blank as illustrated in Fig. 4 and the narrow portion of the blank is then folded over on line 14 into the position shown 95 in Fig. 5, the fold 17 constituting a re-entrant portion or bellows fold of the connected edges of the two sides. The two sides correspond to the front and the back of the bag of Fig. 1.

The end edge portions of the material 100

shown in Fig. 5 and which are of unequal width, the back edge being the longer, are next bent upwardly along the line 18 into the positions shown in Fig. 6. This folded material comprises an end portion of the fold 17. The corner of this fold is then bent inwardly along the diagonal line 19 shown in Fig. 6 and the end fold including the corner folded along the line 19 is then secured in position by suitable adhesive material and the corner portion thus constructed appears as illustrated in Fig. 7.

10 The bottom fold 6 of the bag, which is thus formed, has four thicknesses of material in the major portion of its width across the bag while the corner formed in the manner described above has from six to twelve thicknesses of material in its several parts. The latter number of thicknesses is found at the 20 extreme corner of the bag which is in part formed by the folding of the re-entrant fold 17 at the side of the bag.

15 The top of the bag is closed by the fold 5 with the upper right-hand corner formed in the same manner as that described in connection with the fold 6 and the lower right-hand corner of the bag.

20 The clips 8 and the hook 9 are secured in position, the left-hand side edges are bent 30 into three successive folds to be engaged by the clips 8 and the bag is ready for use.

25 Bags constructed in accordance with my invention may be easily and conveniently assembled and the end closures may be formed automatically by suitable apparatus in such 35 manner as to provide end edges of unusual strength together with corner portions comprising relatively large numbers of thicknesses of material to provide unusual rigidity and strength in those portions that are 40 usually subject to impacts and damage.

105 I claim as my invention :

110 1. A garment bag having two side wall members, folds on a side edge and an end 45 edge of said members, one of said folds including an end portion of the other, and a fold comprising a corner of both the including and the included folds, the corner fold being itself folded within said including fold.

115 2. A garment bag having two side wall members, a longitudinal fold adjacent one side edge of one of said members, a transverse fold on one end of said bag, and a fold comprising a corner of said transverse fold 55 and including a portion of said longitudinal fold, the corner fold being folded within said transverse fold.

120 3. A garment bag comprising a front portion and a back portion that are integral and 60 have a reentrant fold at their connected edge, and an end fold for closing adjacent ends of said front and back portions an having a corner of the reentrant fold folded within it.

125 4. A garment bag comprising a front member and a back member connected at adjacent 65

side edges by a reentrant fold, a transverse fold comprising unequal widths of end edge portions of the respective members, and a diagonal fold of a corner of said transverse fold including a portion of the reentrant fold, 70 said diagonal fold being included within said transverse fold.

5. A garment bag comprising two side members that are integral and have a reentrant fold between adjacent side edges of the 75 respective side members, and a transverse fold comprising end edge portions of said members and having a corner thereof, including a portion of the reentrant fold, folded within said transverse fold.

80 In testimony whereof, I have hereunto subscribed my name this third day of March 1930.

85 RALPH C. STROUT.
